RAT GUARD

Earle H. Carder and Lawrence H. Cook,
Menlo Park, Calif.

Application August 31, 1945, Serial No. 613,820

7 Claims. (Cl. 114—221)

1

This invention relates to rat guards of the type adapted to be clamped on the mooring lines of a ship to prevent rats from boarding or leaving the ship by way of the mooring lines. While many different kinds of devices of this character have been designed, all of these with which we are familiar have one or more undesirable features that make them awkward to apply and remove, expensive to manufacture, or lacking in durability.

One of the objects of this invention is to provide a rat guard that is easy to handle when applying it to or removing it from a mooring line, and that may be quickly manipulated for these purposes, and also one which the rats cannot pass when going in one direction which is generally from the ship to the wharf.

Another object of the invention is to provide a rat guard that is adapted, without adjustment, to be applied quickly and easily to mooring lines of various diameters.

Another object of the invention is to provide a rat guard that is constructed from inexpensive parts that are easily assembled during manufacture.

Still another object of the invention is to provide a rat guard that is durable in service and that will occupy a minimum amount of storage space.

Additional objects and advantages of the invention will become apparent from the following detailed description of one preferred embodiment thereof, taken in conjunction with the accompanying drawings in which:

Fig. 1 is a front elevation of a device embodying the invention showing it applied to a mooring line that is illustrated in section.

Fig. 2 is a fragmentary view showing a portion of Fig. 1 on an enlarged scale, certain parts being broken away for clarity.

Fig. 3 is a sectional view taken along line 3—3 of Fig. 1 but omitting the mooring line.

Fig. 4 is a front elevational view of one of the elements of the guard.

Fig. 5 is a front elevational view of another of the elements of the guard.

The illustrated embodiment of the invention is generally disk-shaped in composite outline and comprises three main parts that are constructed of sheet metal, each resembling in individual outline a portion cut from a disk and having substantially one outer arcuate edge. For convenience these three parts will be referred to in the following description as "disk segments."

The assembly illustrated in Figs. 1 to 3, as

viewed in Fig. 1, comprises a large left hand disk segment 10 and a similar right hand disk segment 11 that are independently pivotally mounted on a smaller intermediate disk segment 12 by a pair of rivet-like pins 13 and 14, the three disk-segments being normally disposed in mutually partially overlapped relation with their outer arcuate edge portions aligned to form a complete circle. The three disk segments have configurations 10 such that when they are disposed together as illustrated an aperture 15 is left in the center of the assembly to accommodate a mooring line 16. Each of the disk segments is provided with a transversely extending gripping plate 17 that is secured to an inner arcuate edge portion of the disk segment forming a part of the boundary of the aperture 15. The three gripping plates 17 provide bearings surfaces in contact with the mooring line 16 along a substantial length thereof.

An inverted U-shaped leaf spring 18 is pivotally secured at one end to the left hand disk 10 by a pin 20 and the opposite end of said spring is secured to the right hand disk 11 by a pivot 21, 25 said pins 20, 21 being positioned above the opening 15 and along adjacent edges of disks 10, 11 and above a line connecting rivets 13, 14. The tension on the spring 18 is such that the legs of the spring tend to move apart thus yieldably 30 urging the lower portions of the disks 10, 11 to overlapping relationship and urging the gripping plates 17 thereon and on plate 12 toward the center of aperture 15 and into tight gripping engagement with the mooring line 16.

35 A pair of handles 23 and 24 are respectively secured to the left and right hand disks segments 10 and 11 in the regions where they overlap the intermediate disk segment 12. Thus, movement of the handles 23 and 24 toward each other causes 40 the left and right hand disk segments to rotate in opposite directions about their respective pin mounting 13 and 14; and this, in turn, causes the adjacent edges of the left and right hand disk segments that are normally in overlapped relation to become separated sufficiently to permit the mooring line 16 to pass therebetween for applying the device to or removing it from the mooring line. This rotation of the left and right hand disk segments is opposed by the springs 18 until 50 the pins 20, 21 move below a straight line extending through pivots 13, 14 at which time the spring tends to move the disk segments to fully separated position (Fig. 2) and to hold them so separated until the handles are moved toward each other and the pins 20, 21 are above said line.

When the device does not have a mooring line passing through the central aperture therein, and no restraint is applied to the handles 23 and 24, the spring 18 causes the left and right hand disk segments to rotate into positions of greater overlap with each other than is shown in Fig. 1, thus reducing the size of the central aperture 15. As the handles 23 and 24 are moved toward each other for separating the normally overlapped edges of the left and right hand disk segments, the central aperture 15 becomes progressively larger; and between positions of maximum and minimum overlap of the left and right hand disk segments, a considerable variation in the size of the central aperture 15 can be effected. This permits the device to be used on mooring lines of a considerable range of sizes without requiring any special adjustment, a characteristic that is desirable both from the viewpoint of the manufacturer and of the user of the device.

In order to maintain the three disk segments 10, 11 and 12 more rigidly in alignment and to counteract a tendency of the device to twist open on mooring lines of certain sizes, oppositely disposed, overlapping ears 25 and 26 are provided on the left and right hand disk segments 10 and 11, respectively, and a pin and slot connection is made between the two ears. For this purpose a pin 27 (Fig. 2) is rigidly secured in an aperture in the ear 26 of the right hand disk segment 11, and a slot 28 is provided in the ear 25 of the left hand disk segment 10. The pin 27 projects through the slot 28 in the ear 26 of the right hand disk segment and is held therein by a rivet-like head on the pin.

As the disk segments 10 and 11 are rotated in the manner described above from the positions illustrated in Figs. 1 and 2, either to open the device or to close it further, the pin 27 moves in the same direction along the slot 28, the length of the slot 28 being made great enough to accommodate the desired extreme positions of the disk segments and the opening of both disk segments is assured should one tend to stick to the mooring line.

The disk segments 10, 11 and 12, described generally above, are illustrated more clearly in Figs. 4, 5 and their individual construction will now be described with greater particularity.

As shown in Fig. 5 the intermediate disk segment 12 comprises a fan shaped sheet of metal having an outer arcuate edge 31 and two adjoining straight edges 32 and 33 that may be reinforced in any suitable manner if so desired. The inner arcuate edge 35 generally corresponds in curvature to a segment of a circle having a diameter similar to that of the mooring line 16 and edges 32, 33 connect with the ends of such edge 35 at their convergent ends. A pair of holes 36 and 37 are drilled or punched through the segment 12 to accommodate the pins 13 and 14 upon which the left and right hand disk segments 10 and 11 are pivotally mounted, and one of the gripping plates 17, as previously described, is secured on inner edge 35.

As shown in Fig. 4 the left hand disk segment 10 comprises a sheet of metal having an arcuate edge 41 and an adjoining straight edge 42 that may be rolled around a length of wire 43 (Fig. 3) to give added stiffness to the sheet. A hole 46 is drilled or punched through the disk segment 10 to accommodate the pin 13 on which the left hand disk segment 10 is pivotally mounted. One of the gripping plates 17 and the pin 20 are also mounted on the left hand disk segment 10, as

mentioned above, in any suitable manner. The handle 23 for this disk segment, that may conveniently consist of a length of rolled steel channel, is also secured on the disk segment 10.

As shown in Figs. 1, 2, 4, taken together, the left and right hand disk segments 10 and 11 are substantially identical in outline but are otherwise substantially opposite in configuration, with certain minor structural differences. The structural features of the latter that differ from the former are clearly shown in Figs. 1, 2. The right hand disk segment 11, like the left hand disk segment 10, comprises a sheet of metal. A hole is provided to accommodate the pin 14 on which the right hand disk segment is mounted, the hole occupying a position corresponding to that of the hole 46 in the left hand disk segment. Instead of a slot 28 in the ear 26 the pin 27 is provided, as mentioned above. One of the gripping plates 17, the pin 21 and the handle 24, also previously referred to, are mounted on the right hand disk segment 11 in positions opposite the positions of the corresponding parts of the left hand disk segment 10.

Though the thickness of the stock from which the three disk segments are constructed is obviously not limited to any precise range of dimensions for an assembly of any given diameter, it is important that it be sufficient to produce a reasonably rigid assembly and any reinforcement may be used if desired.

The outline of the disks 10, 11 has been described with respect to their curved edges 41. The straight edges 42 along their overlapping portions and extending vertically downwardly below aperture 15 when the device is on the mooring line are substantially parallel. The edges 47 along which handles 23, 24 extend are sufficiently divergent in direction away from aperture 15 to enable the disks 10, 11 to be swung apart sufficiently to receive the mooring line in said aperture between spaced edges 45. However, these edges 47 also extend generally vertical.

Ears 25, 26 are closely adjacent the central aperture 15 although spaced sufficiently to not interfere with the mooring line 16 in placing the rat guard on such line or in removing it from the line.

In positioning the device on a mooring line, the operator first moves handles 23, 24 toward each other until the spring 18 automatically will hold disks 10, 11 in open position. Then the operator need merely place the device on the mooring line free from any strain on him in holding the disks 10, 11 apart. After the device is where the operator wishes it to stay, he merely moves the handles toward each other until the force of spring 18 causes the disks 10, 11, 12 to snap to closed position with gripping members 17 tightly gripping the mooring line.

The pin and slot connection between the projecting ears 25 and 26 of the left and right hand disk segments 10 and 11 causes both of these disk segments to pivot simultaneously with respect to the intermediate disk segment 12. This assists in disrupting any tendency of one of the gripping plates 17 on the left or right hand disk segment to stick to a mooring line when the device is being removed therefrom, since both of these gripping plates are simultaneously moved with respect to the third gripping plate on the intermediate disk segment 12, from which the mooring line can be freed by pulling on the handles 23 and 24. The pin and slot connection also adds rigidity to the assembly and assists in preventing the device from

twisting open while it is in place on a mooring line.

In order to insure against the tendency of the segment 12 to become distorted under the tension of spring 18 in operating the device, a channel strip 42 is provided to which one of the ends of rivets 13, 14 may be secured. This strip is formed with a central bridge section 49 spaced outwardly of the disk segments to permit the spring 18 to pass thereunder (Fig. 2) in opening and closing the device.

Where the device shown is used on rather small mooring lines, the overlap along the adjacent edges of the segments 10, 11 may be greater than is shown in Fig. 1 and in order to prevent interference between the rolled outer edges of said segments, it is preferable to shorten the distance between the outer edge of segment 11 adjacent the overlap as indicated at 50 (Fig. 1) so that the said outer edge of segment 11 at point 50 will clear the rolled outer edge of segment 10.

It is highly important to note that the straight edges 32, 33 of segment 12 extend more nearly horizontal than vertical and that these edges are directed downwardly. Thus when the rat guard is positioned on a mooring line with the segment 12 nearest the ship, it is impossible for a rat to pass the guard inasmuch as the rat cannot gain a toehold along the edges 32, 33 or any other edges that are on his side of the guard. The rat is faced with a smooth wall that it cannot climb. Were the edges 32, 33 more nearly vertical or were there any irregularities in such edges, the rat might find it possible to get over the guard but the structure herein described makes this impossible.

We claim:

1. A rat guard adapted to be attached to a mooring line comprising three plates normally disposed in substantially parallel planes in mutually partially overlapped relation and forming in composite outline a disk having a generally circular aperture therethrough partially bounded by each of said plates and adapted to accommodate a mooring line, two of said plates being independently mounted on a third of said plates for pivotal movement with respect thereto about axes normal to the planes of all of said plates whereby adjacent overlapped portions of the pivotally mounted plates may be separated to permit a mooring line to be passed therebetween into position in said aperture, and spring means acting between said pivotally mounted plates for yieldably holding the latter against separation of their adjacent overlapped portions and the portions of said third plate that overlaps a portion of each of said two plates extending generally horizontally when the portions of said two plates that overlap each other extend vertically downwardly.

2. A rat guard adapted to be attached to a mooring line comprising three plates normally disposed in substantially parallel planes in mutually partially overlapped relation and forming in composite outline a disk having a circular aperture therethrough partially bounded by each of said plates and adapted to accommodate a mooring line, two of said plates being independently mounted on a third of said plates for pivotal movement with respect thereto about axes normal to the planes of all of said plates, whereby adjacent overlapped portions of the pivotally mounted plates may be separated to permit a mooring line to be passed therebetween into position in said aperture, and spring means act-

ing between said pivotally mounted plates for yieldably urging the latter toward positions of greater overlapped relation with each other the overlapping portions of said plates being along three substantially equally spaced straight lines extending radially from said aperture with the portions of said two plates that overlap each other extending vertically downwardly from said mooring line when the guard is on the latter.

10 3. A rat guard adapted to be attached to a mooring line comprising three plates normally disposed in mutually partially overlapped relation with their overlapped portions substantially in surface-to-surface contact, said plates being so shaped that they form a substantially annular composite outline with portions of each plate constituting parts of both the inner and outer edges of the annulus, two of said plates being independently mounted on a third of said plates for pivotal movement with respect thereto about axes normal to the planes of all of said plates, said third plate being uppermost when the guard is in use with the portions thereof that are in overlapping relation to said two plates extending generally laterally and oppositely outwardly from the inner edges of said annulus, whereby adjacent overlapped portions of the pivotally mounted plates may be separated to permit a mooring line to be passed therebetween into the aperture of the annulus, and spring means yieldably holding the pivotally mounted plates in their normally overlapped relation.

4. A rat guard adapted to be attached to a mooring line comprising three plates normally disposed in mutually partially overlapped relation with their overlapped portions substantially in surface-to-surface contact, said plates being so shaped that they form a substantially annular composite outline with portions of each plate constituting parts of both the inner and outer edges of the annulus, two of said plates being independently mounted on a third of said plates for pivotal movement with respect thereto about axes normal to the planes of all of said plates whereby adjacent overlapped portions of the pivotally mounted plates may be separated to permit a mooring line to be passed therebetween into the aperture of the annulus, said pivotally mounted plates being respectively provided with ears that project into mutually overlapped relation and are joined by a pin and slot connection adapted to cause the pivotally mounted plates to pivot together in opposite directions, and spring means acting between said pivotally mounted plates for yieldably urging them toward positions of greater overlapped relation with each other.

5. A rat guard adapted to be attached to a mooring line comprising three plates normally disposed in substantially parallel planes in mutually partially overlapped relation and forming in composite outline a disk having a central aperture therethrough partially bounded by each of said plates and adapted to accommodate a mooring line, means pivotally supporting two of said plates on the third for movement of the normally overlapped portions of said two plates from overlapped closed position to a fully spaced open position and vice versa and in which open position the said last mentioned edges are spaced apart sufficiently to permit passage of such mooring line between them to said aperture, means for manually causing said movement, means connected with said two plates automatically operative for holding said two plates in said closed and

in said open position upon movement of said plates to said positions respectively.

6. A rat guard adapted to be attached to a mooring line comprising three plates normally disposed in substantially parallel planes in mutually partially overlapped relation and forming in composite outline a disk having a central aperture therethrough partially bounded by each of said plates and adapted to accommodate a mooring line, means pivotally supporting two of said plates on the third for movement of the normally overlapped portions of said two plates from overlapped closed position to a fully spaced open position and vice versa and in which open position the said last mentioned edges are spaced apart 15 sufficiently to permit passage of such mooring line between them to said aperture, means for manually causing said movement, spring means connected with said two plates automatically operative for holding said two plates in said closed and in said open position upon movement of said plates to said positions respectively.

7. A rat guard adapted to be attached to a mooring line comprising three plates normally disposed in substantially parallel planes in mutually partially overlapped relation and forming in composite outline a disk having a central aperture therethrough partially bounded by each of said plates and adapted to accommodate a mooring line, means pivotally supporting two of said 25 plates on the third for movement of the normally overlapped portions of said two plates from overlapped closed position to a fully spaced open position and vice versa and in which open position

10
5

the said last mentioned edges are spaced apart sufficiently to permit passage of such mooring line between them to said aperture, means for manually causing said movement, spring means connecting said two plates with each other at points on said two plates movable across a straight line connecting the pivots respectively pivotally securing said two plates to said third plate, said spring means being arranged and adapted to yieldably urge said plates to said closed position when said points are at one side of said line and to yieldably urge said plates to open position when said points are at the opposite side of said line.
